UNITED STATES PATENT OFFICE.

SAMUEL E. DIESCHER, OF PITTSBURG, PENNSYLVANIA.

PIERCING-MILL AND THE LIKE.

999,757.

Specification of Letters Patent.

Patented Aug. 8, 1911.

Application filed June 20, 1906. Serial No. 322,532.

To all whom it may concern:

Be it known that I, SAMUEL E. DIESCHER, a citizen of the United States, residing at Pittsburgh, in the county of Allegheny and State of Pennsylvania, have invented or discovered new and useful Improvements in Piercing-Mills and the Like, of which the following is a specification.

My invention relates to piercing mills for manufacturing seamless tubes from solid blanks or billets, but may be used for straightening or other rolling operations.

In the customary practice of making tubes by the combined action of rolls and a piercing mandrel, the friction between the rolls and tubes has been very great, requiring a waste of power and rapid wear and strain of the apparatus. By my invention, I aim to do away with the friction between the rolls and the work, whether the same be a billet, a tube, or a bar.

My invention is disclosed in the three accompanying sheets of drawings, in which:—

Figure 1 is a longitudinal section thereof; Fig. 2, a vertical section thereof on the line 2—2 of Fig. 1, looking with the arrows, the rolls with their frames and driving chains and wheels being shown in elevation; Fig. 3, an end elevation of one of the rolls and its shaft; Fig. 4, a cross-section of one of the rolls on the line of the center of its shaft, the latter being shown in side elevation; and Fig. 5, a plan view of a form of tongs which I may use, one of the hooks being partly broken away.

Referring to the drawings, 1 is the stationary base or frame, which supports the movable portions of my invention. Supported horizontally in said frame is the shaft 2 provided with the driving pulley 3 and the roll-carrying head 4. Movable radially toward and from each other in the head are the pistons 5 operating in the cylinders 6 which have their outer ends beyond the pistons connected by the tubes or passages 7 in the head, shaft and pulley. The outer end of the pulley has the block 8 secured thereto, which contains continuations 9 of the tubes or passages 7 ending in the annular grooves 10 in the stationary ring 11. 12 is a pipe which leads fluid pressure to the groove 10. The pistons 5 have inward prolongation consisting of the racks 13 meshing with the pinions 14 secured to the screws 15 which are parallel and on opposite sides of the center of the shaft 2.

The ends of the screws are oppositely threaded and coöperate with the two sliding frames 16, each carrying a roll 17 on a shaft 18, the rolls being disposed at right angles to the screws and on opposite sides of the center of the shaft 2. Each screw has a pair of sprocket wheels 19, one on each side of the plane including the center of the shaft 2. The sprocket wheels are connected together in pairs by the sprocket chains 20.

The rolls are not rigidly secured to the shafts 19, but have a wobbling motion, which may be provided for in various ways. I have shown the shaft 19 with a bulge, ball or barrel-shaped center 21 with the collar 22 at each end of the bulge, the collar having the inclined shoulders 23 to be engaged by corresponding shoulders 24 at the outer ends of the opening through the roll. This opening conforms to the shape of the collars and the bulge so that the roll can swing at an angle to the shaft 19, as shown by dotted lines on Fig. 4 and may maintain the angle during the rolling operation of the machine. The collars may be modified or omitted entirely, if desired.

Each roll preferably consists of an outer integral annular part 25 and an inner annular sectional part consisting of the half rings 26 held from rotation within the part 25 by means of the rivets 27 lying half in each ring and from separation by the rivets being headed down over both rings, as shown in Fig. 4. The roll and shaft may be otherwise constructed but I would consider my invention to cover any method of connecting the two whereby the principle of their operation is used.

At the front of the frame 1, I secure a table 28 carrying a pair of endless sprocket chains 27 (only one being shown). Movable over this table is a pair of tongs which I prefer to construct as shown on Figs. 1 and 5, though other forms of tongs may be devised without departing from my invention. The tongs shown have the two jaws 30 secured together by the large pivot 31. The reins 32 of the tongs form bell-cranks with their respective jaws and are connected by the links 33 to the cross-head or block 34 through the horizontal pins or pivots 35 on which the block may swing up and down. The block is provided with rearward extensions or hooks 36 for engagement with the links of the chains. The block is provided with a handle 37. The pivot 31 and the

block 34 have an opening in line with the axis of the shaft 2, in which opening is the mandrel 38 having the head 39 normally between the rolls, as shown on Fig. 1. That portion of the block 34 nearest the jaws of the tongs is sufficiently heavy to hold the hooks normally above the chain. The shaft 2 and the block 8 are hollow and provided with the feed tube 40, secured by the set-screw 41 in the cross piece or bracket 42 at the rear of the machine. The bracket 42 has an inclined chute portion 43 to guide the bars to be pierced into the tube 40.

44 designates a billet or bar being pierced. The operation is as follows:—The billet 44 is first heated and pushed into the tube 40 and between the rolls 17 where it engages the mandrel head 39. The shaft 2 being thrown into operation, the billet is pushed past the rolls and grasped by the tongs. As soon as the tongs have their jaws over the end of the billet the hooks 36 are, by raising the handle 37, engaged with the chains 29 which are traveling constantly in the direction of the arrow near the chain 29. The first action of the chains is to close the jaws of the tongs upon the pipe and lift the chains toward the mandrel. Then the chains pull the billet through the rolls and over the mandrel in a manner readily understood. When the billet has passed beyond the rolls, the hooks will be disengaged from the chains by the gravity of the chains and the over-balance of the block 34, and the mandrel and tongs drawn away from the tube. It will be observed that as the pipe is pushed or drawn past the rolls, the latter will have the parts thereof in contact with the billet rocked or swung forward in the direction of the travel of the billet. Where the rolls are set rigidly at right angles to their shafts, the billet has enormous friction against the rolls, as the latter do not assist the billet. Where the rolls are freely mounted so as to swing as described, the draft required to pierce the billets is materially lessened, because each portion of the rolls as they engage the billet move from a point at the rear of the points thereof just passing the billet and swing forward with the movement of the billet without any friction or with a negligible quantity thereof. This forward swing of the rolls is continuous while the machine is in operation.

In operation the rolls 17 need not point forward at a large angle; in fact, the angle may be very small where the speed of the rolls is very rapid, because at every revolution the rolls will swing so as to permit the billet to feed forward without friction a distance equal to the amount which the point in contact with the billet is in advance of the diametrically opposite point. If the revolutions are very many per second, the billet may pass very rapidly without mov-

ing the rolls out of their position at right angles to their shafts. The rolls are fed toward the billets by means of the screws 15 which are operated by fluid pressure in the cylinders 6, acting on the pistons 5. The pistons rotate the pinions 14 on the screws 15. The chains 20 cause the rolls to be both moved to the same degree.

My invention is believed to be a broad one and I do not desire to be restricted to the precise mechanism disclosed. I do not restrict the use of my rolls or their equivalent to piercing mills, but claim protection on the same wherever they prove themselves useful. By merely omitting the mandrel, the machine could be used for straightening. Rolls employing the principle of the rolls shown might be used in machines differently organized. The tongs might be omitted and the billet, bar or other work pushed into and through the rolls. The number of rolls may be increased, if desired.

Having described my invention, I claim:—

1. In a rolling mill, a plurality of shaping rolls arranged to form between them a pass for shaping the cross-section of metal, one of said rolls being mounted to have free rocking movement transverse of its axis.

2. In a rolling mill, a plurality of shaping rolls arranged to form between them a pass for shaping the cross-section of metal, a shaft in one of the rolls, and a universal connection between the roll and the shaft, said connection being constructed to permit free rocking movement of the roll to correspond with the travel of the work through the pass.

3. In a rolling mill, a plurality of shaping rolls arranged to form between them a pass for shaping the cross-section of metal, each of the said rolls being mounted to have free universal movement to correspond with the travel of the work through the pass.

4. In a rolling mill, a plurality of shaping rolls arranged to form between them a pass for shaping the cross-section of metal, a shaft supporting each roll, and a ball and socket connection between one of the rolls and its shaft, said roll being freely movable on said connection.

5. In a rolling mill or the like, a rotary head, a plurality of rolls carried by said head and arranged to form a pass, a plurality of pistons connected one to each roll and arranged when actuated to urge the rolls toward the said pass, and means for supplying pressure simultaneously to all the pistons to set up a tendency of the rolls to move simultaneously toward said pass.

6. In a rolling mill or the like, a shaft, a rotary head thereon carrying a plurality of rolls having a pass between them, pistons and cylinders in said head, said pistons being connected one to each roll and being arranged when actuated to urge the rolls to-

- ward, the said pass; passages in the shaft and head for supplying fluid pressure to said cylinders, and a source of fluid pressure in permanent connection with the said passages in the shaft.
7. In a rolling mill or the like, a rotary head, a plurality of rolls carried thereby, slideable roll-carrying frames in the head, right and left hand screws connecting the frames, and means for rotating the screws.
8. In a rolling mill or the like, a rotary head, a plurality of rolls carried thereby, slideable roll-carrying frames in the head, right and left hand screws connecting the frames, pinions carried by said screws and means engaging the pinions for rotating the same.
9. In a rolling mill or the like, a rotary head, a plurality of rolls carried thereby, slideable roll-carrying frames in the head, right and left hand screws connecting the frames, pinions carried by said screws, racks meshing with said pinions, and means for moving the racks.
10. In a rolling mill or the like, a rotary head, a plurality of rolls carried thereby, slideable roll-carrying frames in the head, right and left hand screws connecting the frames, pinions carried by said screws and means engaging the pinions for rotating the same.
11. In a rolling mill or the like, a rotary head, a plurality of rolls carried thereby, slideable roll-carrying frames in the head, right and left hand screws connecting the frames, pinions carried by said screws, racks meshing with said pinions, independent means for moving the racks, and means for causing the rolls to be adjusted equally.
12. In a rolling mill or the like, a rotary head, a plurality of rolls carried thereby, slideable roll-carrying frames in the head, right and left hand screws connecting the frames, pinions carried by said screws, racks meshing with said pinions, independent means for moving the racks, and a sprocket chain connection between the screws.
13. In a rolling mill, a plurality of rolls arranged to form a pass, a shaft extending through each roll, and a universal connection between each roll and its respective shaft, the periphery of each roll being curved from face to face on the arc of a circle drawn from the center thereof.

Signed at Pittsburg this 18th day of June,
A. D. 1906.
